UNITED STATES PATENT OFFICE.

GEORGE A. JOHNSON, OF CHICAGO, ILLINOIS, ASSIGNOR TO WILLIAM H. MINER, OF CHAZY, NEW YORK.

RAILWAY DRAFT-RIGGING.

1,290,219.

Specification of Letters Patent.

Patented Jan. 7, 1919.

Application filed March 12, 1918. Serial No. 221,904.

To all whom it may concern:

Be it known that I, GEORGE A. JOHNSON, a citizen of the United States, residing at Chicago, in the county of Cook and State 5 of Illinois, have invented a certain new and useful Improvement in Railway Draft-Rigging, of which the following is a full, clear, concise, and exact description, reference being had to the accompanying drawings, forming a part of this specification.

This invention relates to improvements in railway draft riggings.

One object of the invention is to provide a friction draft gear for railway draft rigging, which gear is provided with a large number of friction elements having large frictional wearing areas, the gear being also of unusually high capacity.

Another and further object of the invention is to provide a friction gear for railway draft riggings, wherein all the friction elements may be cheaply manufactured in the form of ordinary castings.

In the drawing forming a part of this specification, Figure 1 is a part side elevation, part longitudinal, vertical, sectional view of a railway draft rigging showing my improvements in connection therewith. Fig. 2 is a vertical, transverse, sectional view, 30 taken on the line 2-2 of Fig. 1. And Fig. 3 is a horizontal, sectional view of a portion of a railway draft rigging showing another embodiment of the invention.

Referring to the construction shown in Figs. 1 and 2, 10-10 denote the channel draft sills of a railway car, to the inner faces of which are secured front and rear stop members 11-11. A draw bar 12 is operatively connected to the draft sill by 40 any suitable yoke-acting means, as for instance, the strap 13.

The shock absorbing mechanism proper, as shown, comprises a front follower A, rear follower B, a front set of wedges C-C, a rear set of wedges D-D, a central friction member E, a front set of upper and lower or side friction members F-F, a rear set of upper and lower or side friction members G-G, four bolts H-H and four main 50 springs J-J.

Each follower A and B is provided on its inner face with a pair of pockets or recesses 14-14 separated by a transversely extending rib 15, the pockets 14 being adapted to loosely receive the ends of the corre-

sponding wedges C-C and D-D. In normal position of the parts, there is a slight clearance, as indicated at 16, between each of the wedge members and the follower rib 15. This is done to compensate for any slight variations in manufacture and also to permit slight adjustment of the wedges on the followers to compensate for wear on the frictional surfaces.

The wedges C-C and D-D are provided at their inner ends with wedge faces 17-17 arranged in opposed pairs, as clearly shown in Fig. 1.

The central friction member E, in the construction shown, is an elongated plate-like member, the ends of which are slidable between the sets of wedges C-C and D-D, the friction member E and the wedges having horizontally extending slidable friction faces. At its center, the friction member 70 E is enlarged so as to provide an upper set of opposed wedge faces 18 and a lower set of opposed wedge faces 19-19. The friction members F-F and G-G are beveled or wedge-shaped on their ends, as indicated at 20 and 21, to coöperate with the wedge faces 17-17 of the wedges C-C and D-D on the one hand and the wedge faces 18-18 and 19-19 on the other hand.

To accommodate the bolts H-H, all of the members E, F-F and G-G are provided with suitable aligned openings, those in the central friction member E being longitudinally elongated, as indicated at 22, so as to permit movement of the bolts H lengthwise of the friction member E. Each of the bolts H carries a slidable spring follower 23 to engage the upper end of the corresponding spring J and a lower follower 24, against which the lower end of the spring J is seated. Each upper follower 23 is provided with an upstanding boss 25 to engage the lower face of the corresponding friction members F and G. As clearly appears from Fig. 2, the bolts H-H are disposed on opposite sides of the arms of the yoke so as to avoid cutting away any of the metal of the latter.

In order to maintain all the friction elements against relative lateral movement, the central friction member E is provided with flanges at the sides thereof, as indicated at 26-26 so as to slightly overlap the sides or ends of the wedges C-C and D-D and friction members F-F and G-G.

Upon either buff or draft, it is evident that the followers A and B will approach each other relatively and in so doing, the wedges C—C and D—D will force the friction elements F—F and G—G apart and against the action of the springs J—J. At the same time, friction will be generated between the ends of the central friction member E and each set of wedges C—C and D—D since the central friction member E will be forced to slide longitudinally under the influence of the friction elements F—F and G—G which engage the wedge portions 18—18 and 19—19 of the central friction member. With my arrangement, I am enabled to obtain an unusually high capacity because of the use of four springs and the duplicated arrangement of friction elements with the floating central friction member E. Furthermore, all of the friction elements may be made in the form of ordinary castings at comparatively small expense.

In the construction illustrated in Fig. 3, the friction elements shown in Figs. 1 and 2 have been turned through an angle of 90° so as to extend the bolts H'—H' horizontally, one of said bolts being extended in one direction through a slot 27 in one sill and the other bolt through a slot 28 in the opposite sill. In this form, the springs J' are located outside of the sills instead of beneath, as in the construction shown in Figs. 1 and 2. The arrangement of friction elements is the same in all substantial respects and the operation is the same as in the structure shown in Figs. 1 and 2. In some cases it may be desirable to extend the springs downwardly and in other cases horizontally to the sides of the sills, depending upon the conditions of the car structure around the draft rigging.

I claim:

1. In a friction shock absorbing mechanism, the combination with relatively movable end followers, of end wedges on the inner faces of said followers, a central friction member frictionally engaging said wedges, said central friction member having also additional wedges associated therewith and located intermediate said end wedges, outer friction members coöperable with all of said wedges, and spring means for resisting relative approach of said followers and acting through said outer friction members.
2. In a friction shock absorbing mechanism, the combination with relatively movable end followers, of a central friction member located between said followers and having friction surfaces at its ends and wedge surfaces intermediate its ends, wedges movable in unison with said followers and having friction surfaces coöperable with the end friction surfaces of said central member, friction members arranged on each side of said central friction member and having

wedge faces coöperable with said wedges and the central friction member, and spring means for resisting relative approach of the followers.

3. In a friction shock absorbing mechanism, the combination with a pair of end followers, each having a pair of wedges detachably mounted on its inner face, the wedges of each pair being spaced, of a central floating friction member having its ends frictionally engaged between the wedges of each pair, said central friction member having a wedge section near its center, and duplicate sets of friction members on each side of said central friction member and coöperable with said wedges and wedge section of the central member.

4. In a shock absorbing mechanism, the combination with end followers each having a pair of wedges mounted on its inner face, said wedges being substantially prevented from movement transversely of the followers, of a floating central friction member frictionally coöperable with said wedges and provided intermediate its ends with a wedge section, friction members on each side of said central friction member, there being one between each wedge and the wedge section of the central friction member, and spring means for resisting relative approach of said followers.

5. In a railway draft rigging, the combination with draft sills, draw bar, and yoke-acting means, of front and rear followers, a pair of wedges detachably mounted on the inner face of each follower, said wedges having friction surfaces extending parallel to the axis of the gear, a central friction plate having its ends frictionally engaging with said friction surfaces of the wedges, said central friction member having wedge surfaces facing in opposite directions and on each side thereof, friction members on each side of the central friction member and having wedge-shaped ends coöperable with said wedges and the wedge surfaces of the central friction member, said side friction members being separable in directions at right angles to the axis of the gear upon relative approach of the followers, and spring means for resisting separation of the side friction members.

6. In a railway draft rigging, the combination with draft sills, draw bar, and yoke-acting means, of front and rear followers, a pair of wedges detachably mounted on the inner face of each follower, said wedges having friction surfaces extending parallel to the axis of the gear, a central friction plate having its ends frictionally engaging with said friction surfaces of the wedges, said central friction member having wedge surfaces facing in opposite directions and on each side thereof, friction members on each side of the central friction member and

having wedge-shaped ends coöperable with said wedges and the wedge surfaces of the central friction member, said side friction members being separable in directions at right angles to the axis of the gear upon relative approach of the followers, and spring means for resisting separation of the said side friction members, said spring means including bolts extending through

the central and side friction members and 10 at right angles to the axis of the gear, and springs mounted on said bolts adapted to be compressed as the said side friction members are separated.

In witness that I claim the foregoing I 15 have hereunto subscribed my name this 26th day of Feb., 1918.

GEORGE A. JOHNSON.
